R. C. MILLER,
CHAIN WRENCH,
APPLICATION FILED SEPT. 13, 1920.

1,373,255.

Patented Mar. 29, 1921.

UNITED STATES PATENT OFFICE.

ROBERT C. MILLER, OF MAYWORTH, NORTH CAROLINA.

CHAIN WRENCH.

1,373,255.

Specification of Letters Patent. Patented Mar. 29, 1921.

Application filed September 13, 1920. Serial No. 409,788.

To all whom it may concern:

Be it known that I, ROBERT C. MILLER, a citizen of the United States, residing at Mayworth, in the county of Gaston and 5 State of North Carolina, have invented certain new and useful Improvements in Chain Wrenches, of which the following is a specification.

This invention relates to a wrench, and 10 more especially to the class of chain wrenches.

The primary object of the invention is the provision of a wrench of this character, wherein pipes, rods or the like of various 15 sizes can be firmly gripped and turned in either direction, without necessitating the remounting of the wrench in working relation thereto, and after adjustment of the same upon the pipe, rod or the like, thus 20 enabling the handling of the work expeditiously and without excessive labor on the part of the user of the wrench.

Another object of the invention is the provision of a wrench of this character, wherein 25 the gripping chain is mounted and adjusted in the jaw end of said wrench in a novel manner and said jaw end is of a formation to assure positive gripping action upon the work.

30 A further object of the invention is the provision of a wrench of this character, wherein maximum leverage can be had when the wrench is engaged with the work, without the possibility of the said wrench 35 slipping and a maximum range of adjustment is assured so that the wrench is adaptable for large or small work, the gripping chain being readily and quickly adjustable to accommodate the work in the wrench.

40 A still further object of the invention is the provision of a wrench of this character, which is extremely simple in construction, possessing but few parts, thoroughly reliable and efficient in its purpose, strong yet comparatively light in weight, durable, and inexpensive to manufacture.

With these and other objects in view, the invention consists in the features of construction, combination and arrangement of 50 parts, as will be hereinafter fully described, illustrated in the accompanying drawing,

and pointed out in the claims hereunto appended.

In the accompanying drawing:

Figure 1 is a fragmentary top plan view 55 of a wrench constructed in accordance with the invention shown applied to a pipe.

Fig. 2 is an edge elevation, showing the wrench at the jaw end thereof partly broken away.

Fig. 3 is a perspective view showing in detail the latch cam or locking member.

Similar reference characters indicate corresponding parts throughout the several views in the drawing:

Referring to the drawing in detail, A designates generally a portion of a pipe section, which is merely shown to illustrate the application of the chain wrench constituting the present invention and hereinafter 70 fully described.

The chain wrench comprises a handle or lever portion 5, which may be of any desirable length and can be constructed from any suitable material, preferably metal, one 75 end being enlarged to constitute a head 6, which in this instance is of irregular or substantially diamond shape for the major portion thereof and this portion is formed by reducing the width of the head 6 to provide an intermediate web 7 between a pair of 80 stationary jaws 8, the same being identical to each other and are mounted on opposite sides of the web 7. The jaws 8 are preferably riveted to the web 7, yet the same may be otherwise fastened, if found desirable.

The free or outer ends of the jaws 8 are concaved and have formed thereon on opposite sides of the center of the same, reversely set gripping teeth 9 adapted to bite into a 90 piece of work when the wrench is engaged therewith to avoid any possibility of the slipping of the said jaws 8 upon the same.

The particular shape of the web 7 provides between the jaws 8 ways 10 and 11 respectively for accommodating the end portion of a flexible link gripping chain 12, the terminal link 13 of said chain being engaged and secured in the way 10 by a pivot pin 14 and the link next to said terminal link 13 of 95 100 the chain is trained over a guide pin 15 at the inner side thereof, which pin 15 is read-

ily removable if found desirable and is carried in the jaws 8.

The intermediate portion of the chain 12 is adapted to be trained over and about a piece of work, for example, in the manner as shown in Figs. 1 and 2 of the drawing relative to the pipe A shown therein. The other end portion of the chain is adjustably passed through the way 11 and is adapted to 10 be seated in a concavity 16 formed in the edge of the web 7 and this end portion of the chain is adapted to be locked or secured in a manner presently described.

Formed in the jaws 8 and intersecting the 15 way 11 are corresponding inclined slots 17 which are inclined forwardly and accommodate the pivot or axle 18 of a locking eccentric or cam 19 having a lever or arm 20, the pivot or axle 18 being readily slideable in the 20 slots 17 for bringing the cam 19 closely to or away from the end portion of the chain 12 passed through the way 11 and on the turning of said cam 19 by the lever 20 in one direction the end portion of the chain 25 will be firmly secured or held fast in the way 11 and in this manner the jaws 8 and the gripping chain 12 are brought into gripping relation to the piece of work as for example the pipe A as shown in Figs. 1 and 2 of the 30 drawings.

By arcuately moving the handle 5 of the jaw in either direction the piece of work or pipe A can be readily turned by the wrench without any liability of the slipping 35 of the work or the wrench relative to each other.

When it is desired to slacken the chain 12 or loosen the same about the piece of work, the lever 20 is thrown in a direction to dis- 40 engage the cam 19 from the end portion of said chain passed through the way 11 between the jaws 8 of the wrench and when required the said chain can be released from the work. It is clearly apparent that pipes, 45 rods or the like of variable sizes can be engaged by the wrench and turned in either direction as the occasion may require, without possibility of lost motion or the slipping of the chain or piece of work when the 50 wrench is active.

Now in event that the gripping teeth 9 on the jaws 8 should become worn or mutilated to be ineffective the outer knife edge end 21 of the web 7 will then become active

upon a piece of work to prevent the possi- 55 bility of the slipping of the jaws 8 when the wrench is engaged therewith.

From the foregoing it is thought that the construction and manner of use of the wrench will be clearly understood and therefore a more extended explanation has been omitted. It is contemplated to make changes, variations and modifications in the invention as come properly within the scope of the appended claims, without departing 60 from the spirit of the invention or sacrificing any of its advantages.

What is claimed is:

1. A wrench of the character described, comprising a head having spaced jaws pro- 70 vided with a seat formed with reversely dis- posed biting teeth, and also having ways, a chain having one end fixed to one way and its other end slidably passed through the other way, the last mentioned way having 75 a convex inner wall, and a hand operable member in the head for engaging the last named end of the chain to adjustably clamp the latter against said concave inner wall.

2. A wrench of the character described, 80 comprising a head having spaced jaws pro- vided with a seat formed with reversely dis- posed biting teeth, and also having ways, a chain having one end fixed to one way and its other end slidably passed through the 85 other way, a hand operable member in the head for engaging the last named end of the chain to adjustably fasten the same, a guide pin arranged to maintain the fixed end of the chain in its way, and a cam on said 90 member to coact with the chain.

3. A wrench of the character described, comprising a head having spaced jaws pro- vided with a seat formed with reversely dis- posed biting teeth, and also having ways, 95 a chain having one end fixed to one way and its other end slidably passed through the other way, a hand operable member in the head for engaging the last named end of the chain to adjustably fasten the same, and 100 a cam on said member to coact with the chain, said jaws being provided with inclined guide slots for the member, to bring the latter to and from the path of the chain.

In testimony whereof, I affix my signature: 105
hereto.

ROBERT C. MILLER.
